UNITED STATES PATENT OFFICE.

J. MILLER KELLY, OF ROCHESTER, NEW YORK.

LOCOMOTIVE HEAD-LIGHT.

SPECIFICATION forming part of Letters Patent No. 283,254, dated August 14, 1883.

Application filed June 18, 1883. (No model.)

To all whom it may concern:

Be it known that I, J. MILLER KELLY, of Rochester, New York, have invented certain Improvements in Locomotive Head-Lights, of which the following is a specification, reference being had to the accompanying drawings.

My present improvements in locomotive head-lights relate to the application thereto of a signal consisting of a curved colored-glass plate sustained by a suitable frame pivoted to the front of the head-light in such fashion that the signal may be displayed as a bar of colored light passing across the cone of rays emitted from the burner; or it may be concealed by being turned aside and folded up alongside of the light-opening in the front of the head-light.

My improved signal for locomotive head-lights is represented in the annexed drawings, in which—

Figure 1 is a front elevation of a locomotive head-light embodying my present invention. Fig. 2 is a side elevation of the same. Fig. 3 is a partial plan view of the same. Fig. 4 is a transverse section through the curved colored-glass signal and its supporting-frame.

In the accompanying drawings, A represents the case or body of the head-light, which incloses a reflector, B, and burner C, and is of any ordinary or preferred size and construction. The front of the head-light is provided with the usual circular projecting flange or goggle, D, which sustains the glass plate through which the rays of light from the burner are projected forward by the reflector. To the opposite sides of the goggle is pivoted the curved frame L, which carries the curved colored-glass signal G. The frame and colored glass are made of such shape that when the signal is not displayed in front of the head-light it may be folded up alongside of the goggle, being protected, if desired, in this position by the casing E. The sustaining-frame L may be attached to the goggle, so that when folded up it may rest either above or below or at one side of the goggle. When arranged, as shown in the accompanying drawings, to project forward horizontally in front of the head-light when displayed, and to be thrown out of use by being turned up above the goggle, the signal is supported in the horizontal

position by the lug or lugs I I', attached to the front edges of the goggle, and the hook or spring-catch F may be employed to secure it when folded up. If arranged to swing in any other way than that above described, the signal should be provided with suitable hooks or spring-catches to secure it in the displayed position, its weight serving to hold it in place when folded beneath the goggle. The frame L may be constructed in any suitable manner, so as to sustain the curved glass G, it being preferably made, as represented in Fig. 4, so as to inclose the glass at its upper and lower edges. The frame may be pivoted directly to the sides of the goggle; or suitable lugs may be attached thereto for this purpose; or the frame may be pivoted to the ears H H', projecting outward from the front of the head-light. The casing E consists of a curved strip of sheet metal affixed to the head-light case, and projecting forward therefrom at a suitable distance from the outside of the goggle. The casing is not shown in Fig. 3 of the annexed drawings.

It is obvious that my improved signal may be attached to head-lights in which the glass plate which protects the burner and reflector is attached directly to the front of the head-light casing; but I prefer to use it in connection with the goggle, as herein shown. The colored-glass plate G may be of any suitable length or width. The curved form of the glass plate G not only enables the signal to be folded aside and concealed from view, when not in use, in the smallest space possible, but it also serves to distribute the light, rendering the signal distinctly visible at any angle in front of the locomotive.

It is obvious that letters or figures representing the number of the engine or the number or character of the train may be painted on or otherwise attached to the colored-glass plate constituting my improved signal.

I am aware that transparent colored signals have been constructed in various forms and connected in various ways with head-lights, so as to be illuminated thereby, and this I do not broadly claim.

I claim—

1. In combination with a locomotive head-light, a changeable signal consisting of a curved frame containing a curved colored

glass, said frame having its ends attached to the front of the head-light on opposite sides, substantially as described, whereby the glass may be adjustable in front of the light to swing 5 over against the front of the body.

2. In combination with the head-light, the curved frame provided with the colored glass, pivoted at its ends to opposite sides of said light, in combination with means, substantially as described, for sustaining said frame 10 in a displayed position.

3. In combination with the head-light, the curved frame provided with colored glass, and pivoted at opposite ends to the body in such

manner as to swing vertically, in combination 15 with means, substantially as described, for holding said frame in the horizontal and the vertical positions, as described.

4. A swinging attachment for head-lights, the same consisting of a frame containing a 20 colored glass, said frame being curved to encircle the transparent face of the head-light, and being adapted for a pivotal connection at its ends to said light.

J. MILLER KELLY.
